(57) **CLAIM**

The ornamental design for a hair fiber sprayer, as shown and described.

DESCRIPTION

FIG. 1 is an isometric view of the hair fiber sprayer;
 FIG. 2 is a side view of the hair fiber sprayer;
 FIG. 3 is a bottom view of the hair fiber sprayer;
 FIG. 4 is a top view of the hair fiber sprayer;
 FIG. 5 is a first end view of the hair fiber sprayer; and,
 FIG. 6 is a second end view of the hair fiber sprayer.
 The broken lines shown along the bottom of the sprayer illustrate portions of the article and form no part of the claimed design.

1 Claim, 6 Drawing Sheets(56)
